[57] **ABSTRACT**

An electrophotographic process comprising the steps of (a) applying a first charge by means of direct current corona discharge to an overcoated photosensitive sheet consisting of a conductive base, a photoconductive layer and a surface insulating layer; (b) applying a second charge to the so charged sensitive sheet by means of a corona discharge current of asymmetrical wave form in which the discharge current of a polarity opposite that of the first charge is greater than that of the same polarity and the degree of asymmetry is sufficient to satisfy the specified requirements, and simultaneously exposing the sensitive sheet through or original having an image pattern of light and shadow; and (c) thereafter exposing the photosensitive sheet to an uniform illumination over the entire surface to form a latent electrostatic image of the light area and a latent electrostatic image of the dark area, which are of opposite polarity to each other.

**ELECTROPHOTOGRAPHIC PROCESS USING
CORONA DISCHARGE CURRENT OF AN
ASYMMETRICAL WAVE FORM**

This invention relates to a new electrophotographic process. More specifically, the invention relates to an electrophotographic process which can form on the surface of an overcoated photosensitive member a latent electrostatic charge image of a given polarity of the light area and at the same time a latent electrostatic charge image of the opposite polarity of the dark area.

An electrophotographic process for forming a latent electrostatic image corresponding to an original copy by simultaneously charging and imagewise exposing an overcoated photosensitive member, e.g., a three-layered overcoated photosensitive member consisting of a conductive base, a photoconductive layer and a surface insulating layer, is known, for example from, Japanese Pat. application publication No. 4121/1961.

In Japanese Pat. application publication No. 2478/1968 an improvement of the foregoing electrophotographic process is provided comprising a method which comprises impressing the aforesaid overcoated photosensitive member with a direct current voltage of specific polarity by means of a corona discharge, then exposing this photosensitive member to a light image while applying the photosensitive member with a direct current corona discharge of a polarity opposite that of the first charge, and thereafter exposing the photosensitive member to a uniform illumination over the entire surface area by means of an activating radiation. According to this method, the surface of the photosensitive member is charged first with, for example, a positive charge. Next, as a result of a second charge and the exposure of an optical image, the light area and the dark area of the photosensitive member are both charged with, for example, a negative charge. Now, when the photosensitive member is exposed to uniform illumination over the entire surface area by means of activating radiation, the surface potential of the dark area decays. Thus, it becomes possible to increase the contrast of the potentials between the latent electrostatic images of the light area and the dark area. In this case it is theoretically possible to make the surface potential of the dark area positive if the process is so conducted that the positive charge by means of the first charge is not completely neutralized by means of the negative charge of the second charge. However, the direct current negative corona discharge is not as stable as the positive corona discharge or the alternating current corona discharge. Therefore, it is practically impossible to effect the charging uniformly especially with a low charge density (see, for example, Japanese Pat. application publication No. 21432/1966). Further, even one attempts to control the extent of the charge by means of the charging time, this is practically impossible to do, since the charging must be terminated at a period when the charging potential charges very violently. As a result, from the standpoint of forming a stable and clear image, it is nearly impossible to operate such that the positive charge resulting from the first charging is not completely neutralized by the negative charge resulting from the second charging. Therefore, it is highly difficult from the practical standpoint to form by this method an opposite polarity between the latent electrostatic images of the light and dark areas.

On the other hand, in Japanese Pat. application publication No. 23910/1967 a method is disclosed which consists of the steps of applying the aforesaid overcoated photosensitive member with a direct current voltage of specific polarity by means of a corona discharge, and next applying this photosensitive member with an alternative corona discharge while exposing it at the same time to an optical image and thereafter exposing the photosensitive member to a uniform illumination over the entire surface area by means of an activating radiation. While this method possesses the advantage that the instability of the negative corona discharge can be avoided, the reversing of the polarity of the charges of the latent electrostatic images of the light and dark area is theoretically impossible.

In electrophotography the reversion of the polarity of the charges of the images of the light and dark areas is very desirable to increase the contrast of the image formed as well as for solving the soiling of the background by prevention of the so-called fogging during the development operation. Further, if the polarities of the surface potential of the two are also reversed, the developing toner particles in adhering to the latent electrostatic image of opposite polarity during the development operation also receive an electrostatic repulsive force from the latent electrostatic image area of the opposite polarity to result in an efficient accomplishment of the development. In addition, it becomes possible to freely obtain either a positive or negative image by a suitable choice of the developing toner particles.

It has now been found that when in the hereinbefore described electrophotographic methods, which use the overcoated photosensitive member, the second charging is conducted by means of a specific corona discharge current of an asymmetric wave form in which the corona current of a polarity opposite that of the first charging is greater than that of the same polarity, it is possible to form latent electrostatic light and dark images whose polarities are opposite to each other.

Thus, an electrophotographic process is provided according to the present invention, which process comprises the steps of applying a first charge by means of a direct current corona discharge of a specific polarity to either a three-layered overcoated photosensitive member consisting of a conductive base, a photoconductive layer and a surface insulating layer or a four-layered overcoated photosensitive member consisting of a conductive base, a photoconductive layer, a surface insulating layer and an intermediate insulating layer disposed either within the photoconductive layer or between the photoconductive layer and the conductive base; applying to the so charged photosensitive member a second charge by means of a corona discharge current of an asymmetrical wave form in which the discharge current of a polarity opposite that of the first charge is greater than that of the same polarity and simultaneously exposing the photosensitive member through an original having an image pattern of light and shadow, the degree of asymmetry of the corona discharge current of an asymmetrical wave form being in this case sufficient to transform both the polarities of the charged potentials of the light and dark areas of the photosensitive member to opposite polarities and also sufficient to form during the uniform illumination over the entire surface area of the photosensitive member a latent electrostatic image of the dark area of the same

polarity as that of the first charge and a latent electrostatic image of the light area of an opposite polarity to that of the first charge; and thereafter exposing the photosensitive member to a uniform illumination over the entire surface area by means of an activating radiation to form a latent electrostatic light image and a latent electrostatic dark image, which are of opposite polarity to each other.

The invention will now be fully described with reference to the accompanying drawings, wherein:

FIGS. 1-a to 1-c are views illustrating the sectional construction of the photosensitive member used in the process of the present invention;

FIGS. 2-a to 2-c are views explaining the several steps of the process of the present invention;

FIGS. 3-a to 3-c are charts illustrating the changes in the potential of the photosensitive member as a whole, the surface of the insulating layer and at the interface of the insulating layer and the photoconductive layer;

FIGS. 4-a and 4-b are respectively a wiring diagram of the normal alternating current corona discharge apparatus and a graph showing the wave form of the symmetric discharge current obtained therefrom;

FIGS. 5-a to 8-a and FIGS. 5-b to 8-b are wiring diagrams of apparatus for obtaining the asymmetric corona discharge, as used in the present invention, and graphs showing the wave forms of the asymmetric corona discharge currents obtained therefrom; and

FIG. 9 is a schematic view of an apparatus for practicing the process of the present invention.

The overcoated photosensitive member used in the invention consists of either three or four layers. The photo sensitive material shown in FIG. 1-a is made up of a conductive base 1, atop which is superposed a photoconductive layer 2 and a surface insulating layer 3. Instead of providing a single insulating layer, an intermediate insulating layer can be disposed inside the photoconductive layer or between the photoconductive layer and the conductive base. For example, the sensitive material may be as shown in FIG. 1-b, i.e., an overcoated assembly consisting of a conductive base 1, a first photoconductive layer 2, an intermediate insulating layer 3', a second photoconductive layer 2' and a surface insulating layer 3; or as shown in FIG. 1-c, i.e., a overcoated assembly consisting of a conductive base 1, an intermediate insulating layer 3', a photoconductive layer 2 and a surface insulating layer 3.

The photoconductive layer is that which is known per se and any may be used as desired. For instance, a photoconductor or a combination of a photoconductor and a binder can be used as the photoconductive layer. The photoconductor are such as inorganic photoconductive includes material materials such as selenium, zinc oxide, cadmium sulfide, zinc cadmium sulfide, cadmium telluride, (DdTe), selenium telluride (SeTe), cadmium selenide (CdSe) and antimony trisulfide (Sb₂S₃), and such organic photoconductive materials as anthracene, anthraguinone and polyvinyl carbazole. These photoconductors can be used per se as the photoconductive layer. For instance, selenium or cadmium sulfide can be vapor deposited on a suitable base, or a resin which in itself possesses photoconductive properties, e.g., polyvinyl carbazole, can be applied to a base to form the photoconductive layer.

Alternatively, a photoconductor can be first dispersed in a binder and then this can be applied to a conductive base. As the binder, in addition to inorganic

binders, such as water glass, resinous binders are useable. The resinous binders, which can be used, include such as a styrene polymer or copolymers thereof, polyvinyl acetate or copolymers thereof, acrylic resins, polyvinyl acetals or their copolymers, polyvinyl alcohol, polyolefins or copolymers thereof, alkyd resins, polyester resins, silicone resins, epoxy resins and synthetic rubbers. Suitable binders are disclosed in British Pat. No. 1,020,506.

- 10 To increase the sensitivity of the photoconductor to a light source the photoconductor can be treated with an optional sensitizing dyestuff such as rose bengal or methylene blue. Again, the photoconductor may be used after activating with a metal such as gold or copper. 15 In addition, to improve such properties as the pre-exposing effects (light fatigue effect) and the dark resistance of the photoconductor, the surface of the photoconductor can be treated with a Lewis acid, fatty acid or metal salts thereof and organic phosphoric acid ester compounds.

As the conductive base, which supports the photoconductive layer, metallic base plates of such as aluminum or copper, as well as metallic vapor deposited or plated resins, conductive resins, papers applied a hydroscopic salt or a conductive substance, and base plates applied a composition of a metallic powder and a resin can be used. The base plate may be either a flat plate or one which is cylindrical in shape.

As the insulating layer, the transparent dielectrics having high dielectric strength such, for example, as the films of polyesters, cellulose esters, polystyrene and polyolefins are conveniently used.

In FIGS. 2-a to 2-c, which are views illustrating the processing steps, a first charge is applied by means of 35 a direct current corona discharge from a charging apparatus 4 having an electrode 5, to an overcoated assembly consisting of a conductive base 1 atop which is coated integrally a photoconductive layer 2 and a surface insulating layer 3, the charge being applied from above the surface insulating layer (FIG. 2-a: first charge). In FIG. 2-a the surface of the surface insulating layer 3 becomes charged up to potential 6 due to a charge of a given polarity (e.g., positive). On the other hand, the interface portion between the photoconductive layer 2 and insulating layer 3 becomes charged up to a potential 7 due to a charge of opposite polarity (negative). When the photoconductor is a negative type semiconductor in this case, the surface of the photoconductive layer is applied a positive electrostatic charge by applying the electrode with a positive discharge voltage. On the other hand, when the photoconductor is a positive type semiconductor, the surface of the photoconductive layer is applied a negative electrostatic charge by applying the electrode with a negative discharge voltage. While the corona discharge voltage of the first charge varies depending upon the length of the discharging path as well as the bind of the photoconductor, generally speaking, voltage ranging between about 5,000 and about 10,000 volts is preferred.

Next, the photosensitive member, which has been applied the first charge, is applied a charge of a corona discharge current of an asymmetric wave form from a charging apparatus 9 having an electrode 10; at the same time the photosensitive member is exposed to an image pattern of light and shadow (FIG. 2-b: deemed charge-image exposure). While the corona discharge current of an asymmetrical wave form and the expo-

sure are preferably conducted at the same time, it need not be necessarily at the same time in the case where the change from the light resistance to the dark resistance of the photoconductor used as the photosensitive layer is not rapid. In this case the corona discharge current of an asymmetrical wave form may be applied immediately after the exposure. The charge by means of the corona discharge current of an asymmetrical wave form, as herein used, must be one in which the discharge current of a polarity opposite that of the first charge is greater than that of the same polarity and moreover must be one which has a degree of asymmetry sufficient to change the polarities of the potentials of both the light and shadow portions of the image pattern of the photosensitive member to opposite polarities as well as to form an electrostatic latent image of the dark area of the same polarity as the first charge and an electrostatic latent image of the light area of a polarity opposite that of the first charge during the uniform illumination over the entire surface area of the photosensitive member. As a result of this second charge and the exposure, at the light image portion (L) the photoconductive layer 2 becomes conductive and the charge at the interface of the surface insulating layer 3 and the photoconductive layer 2 is caused to disappear to result in the potential becoming equal to the potential of the conductive base (ground potential), and at the same time, due to the asymmetric current charge the surface of the insulating layer 3 is charged with a polarity (negative) opposite that of the first charge to result in a new potential 6''. On the other hand, at the dark image portion (D), due to the photoconductive layer 2 being nonconductive, the charge at the interface of the photoconductive layer and the surface insulating layer formed by the first charge remains, and therefore the potential 7 is maintained and the charge of the surface of the insulating layer formed by the first charge being slightly neutralized by the corona discharge current of asymmetrical wave form becomes a new potential 6'. Thus, the polarity of the surface potential of the photosensitive member becomes as a whole opposite that of the first charge.

Next, when this sensitive material is exposed to uniform illumination over the entire surface area with an activating radiation from a light source 11, the shadow image portion D of the photoconductive layer 2 of the photosensitive member also becomes a conductive layer, and the interfacial potential 7 between the photoconductive layer 2 and the insulating layer 3 becomes equal to the potential of the conductive base (ground potential). While it is preferred to carry out the uniform illumination over the entire surface of the photosensitive member in this step, similar results can be obtained by not performing this uniform illumination of the photosensitive member but by allowing the charge of the foregoing interface to disappear by providing a sufficient period of time before submitting the photosensitive member to the development step which follows, or by carrying out the development in an ambient light. Thus, there is formed, along with the charges and the potentials resulting therefrom a latent electrostatic image of the light portion (6'', L) of a polarity opposite that of the first charge and a latent electrostatic image of the dark portion (6', D) of the same polarity as that of the first charge (FIG. 2-c: overall uniform illumination).

The so prepared sensitive material having electrostatic latent images in which the polarities of the charges of the light image portion and the dark image portion differ from each other can be then developed by methods which per se are known. For instance, in developing the charged image (6') of the dark image portion (D) such as of FIG. 2-d, development by means of the use of toner particles (6't) having a charged polarity opposite that of the charge of the dark portion (D) will do. On the other hand, in developing the charged image (6'') of the light image portion (L), development by means of the use of toner particles (6''t) having a charged polarity opposite that of the light image portion (L) will do. Thus, in accordance with the invention process, the negative and positive images can be developed by choosing, as required, toners either positively or negatively charged. In addition, since the background of the image is charged with a polarity opposite that of the latent electrostatic image to be developed, the toner particles receive simultaneously an attractive force of the static surface charge of opposite polarity and a repulsive force of the static surface charge of the same polarity to make it possible to carry out the development with greater efficiency. As a result, there is no soiling of the background.

As the developer, such developers as the powder developer, liquid developer and mist developer are usable. Again, any of the developing procedures can be employed, such as magnetic brush method, the cascade method, the powder cloud method, the liquid developing method and the mist developing method.

The toner image formed can, if desired, also be transferred to an optional sheet material.

The changes in the potentials of overcoated photosensitive member as a whole and of the insulating layer surface as well as at the interface of the insulating layer and photoconductive layer with the passage of time as the photosensitive member proceeds through the several steps are shown in FIG. 3-a to 3-c. FIG. 3-a shows the surface potential of the photosensitive member as a whole, and FIG. 3-b and 3-c show respectively the potentials of the insulating layer surface and the potential at the interface of the photoconductive layer and the insulating surface layer. When the photosensitive member is applied with a direct current corona discharge of a given polarity by the first charge (I), the potential of the insulating layer surface reaches a' and that of the photoconductive layer and the surface layer interface reaches a'', while the overall potential reaches $a=a'+a''$. Next, when simultaneously with the exposure the corona discharge current of asymmetrical wave form (II) is carried out, the potential of the photoconductive layer and the surface layer interface at the shadow image portion (D) decays slightly by means of the dark decay and reaches $b''D$. On the other hand, the potential of the insulating surface layer decays as a result of the corona discharge current of asymmetrical wave form and reaches $b'D$ (In this case since the charge of the insulating surface layer resulting from the first charge is restrained by the charge of the photoconductive layer and the surface layer interface, it remains the same polarity as that of the first charge even after charging with the asymmetric discharge current). Thus, the surface potential of the photosensitive member as a whole becomes $bD=b'D+b''D$, a polarity opposite that of the first charge.

In contrast, in the case of the light image portion (L), the potential of the photoconductive layer and surface layer interface, due to the light decay, becomes equal to that of the conductive base, i.e. zero potential ($b'L$), while the potential of the insulating surface rapidly diminishes as a result of the corona discharge current of the asymmetrical wave form to become a potential of a polarity opposite that of the first charge ($b'L$), with the consequence that the surface potential of the light image portion as a whole becomes $bL = b'L + b'L$.

Finally, when the photosensitive member is submitted to a uniform illumination over the entire surface area, the potential of the insulating layer surface does not change, but the potential of the photoconductive layer and the surface layer interface of the dark portion D becomes equal to the ground potential ($c'D$) due to the light decay, and the surface potential of the photosensitive member as a whole becomes at the light portion (L) a potential cL , which is opposite in polarity to that of the first charge, while at the dark portion (D) becomes a potential cD , which is the same polarity as that of the first charge.

Thus, the use as the corona discharge for the second charge according to the new method of this invention of corona discharge current of the asymmetrical wave form in which the discharge current of a polarity opposite that of the first charge is greater than that of the same polarity is entirely different from the case where a direct current or an alternating current corona discharge is used as the second charge. That is, when a corona discharge current of the asymmetrical wave form is applied, the charge at the interface of the photoconductive layer and the surface insulating layer at the light image portion readily disappears by exposure to light, with the consequence that the potential of only the insulating layer surface, as compared with the case where a normal alternating current corona discharge is applied (in this case decay to only zero potential takes place), rapidly reaches saturation at a given value of opposite potential, which value is determined by the degree of asymmetry of the asymmetric corona discharge current of the asymmetrical wave form. On the other hand, even at the point when the potential of the insulating layer surface of the light portion, after having inverted to an opposite potential, has nearly reached saturation (which the change of potential with respect to time is small), the potential at the dark portion does not become an opposite potential, because the charge at the aforesaid interface does not readily disappear owing to the dark resistance of the photoconductive layer. Therefore, when the photosensitive member is submitted to a uniform illumination over the entire surface at this time, the aforesaid charge at the dark portion is caused to disappear by illumination and the potential of the interface and the ground potential are equalized, with the consequence that an image portion corresponding to the exposed portion (L) and an image portion corresponding to the unexposed portion (D) of the photosensitive member can be easily formed as latent electrostatic images having polarities different from each other. In the development step, which follows, it becomes possible to obtain either a negative or positive image by the mere choice of the polarity of the toner particles. In either case clear images of high contrast and a minimum of fogging, i.e., whose background is clean, can be obtained.

The corona discharge current of asymmetrical wave form to be used in the invention process can be produced by an optional method. FIG. 4-a shows a conventional alternating corona discharge current generating apparatus. When the primary side 14 of the high voltage transformer is connected to a commercial alternating current source and the two terminals of the secondary side 12 are connected to the electrode 10 and the opposite electrode 13 of the corona generating apparatus 9, an alternating corona discharge current is produced between the electrode 10 and the opposite electrode 13. The current wave form of this corona discharge, as shown in FIG. 4-b, is of normal wave form. The present invention uses a corona discharge which 15 differs from this normal wave form discharge and is an asymmetrical wave form in which a discharge current of a given polarity is greater than the discharge current of opposite polarity. To accomplish this, the wiring is as shown in FIG. 5-a. One 20 terminal of the high voltage transformer is connected to the corona discharge electrode 10 through the intermediary of a rectifier 15 and a resistor 16 connected in parallel, and the other terminal of the transformer is connected to the opposite electrode 13. The wave form 25 of the corona discharge current obtained by such a wiring becomes one in which, for example, the discharge current of the positive side is restrained while that of the negative side is substantially not restrained, i.e., an asymmetric wave form. In this case the magnitude of 30 the discharge current of a given polarity can be freely regulated by changing the value of the resistor 16 connected in parallel with the rectifier 15, and the degree of asymmetry of the wave form of the current can be easily regulated by adjusting the value of the resistor. Alternately, the discharge current of a given polarity can be restrained, as shown in FIG. 6-a, by providing 35 a controlling grid 17 between the corona discharge electrode 10 and the opposite electrode 13 applying the controlling grid with a direct current voltage from a direct current source 18. In this case also the wave form of the current of the corona discharge becomes asymmetric, as shown in FIG. 6-b, and the degree of asymmetry of the wave form of the current can be regulated by adjusting the voltage that this controlling grid 40 45 17 is applied with. Further, as shown in FIG. 7-a, instead of providing a controlling grid between the corona discharge electrode 10 and the opposite electrode 13, an shield 9 which upper side is optically opened disposed in proximity to the discharge electrode 10 can be 50 connected to a direct current voltage source 19, and by applying this shield with a direct current voltage the corona discharge of a given polarity can be restrained, with the consequence that an alternating current corona discharge current having an asymmetric wave form, 55 as shown in FIG. 7-b, can be obtained.

Further, as shown in FIG. 8-a, one terminal of the secondary side 12 of the high voltage transformer can be grounded through the intermediary of a direct current voltage source 20, while the other terminal of the transformer is connected to the corona discharge electrode 10 and the opposite electrode 13 is grounded. As a result, a direct current bias voltage is applied relative to the normal alternating current, and a corona discharge current having an asymmetric wave form, as shown in FIG. 8-b, is obtained.

In all the foregoing cases, as the alternating current one ranging between 5,000 and 10,000 volts is conve-

niently used. The degree of asymmetry of the corona discharge current of asymmetrical wave form used in the invention is preferably one in which the ratio of the discharge current of a polarity opposite that of the first charge (i_1) to the discharge current of same polarity as the first charge (i_2) is a ratio $i_1:i_2=10:1$ to $10:9$, and preferably $5:1$ to $2:1$.

The invention process can be employed for reproduction purposes by the use of an apparatus such as shown in FIG. 9.

Referring to FIG. 9, a photoconductive sensitive layer 2 and a surface insulating layer 3 are disposed on a cylindrical conductive base member 1. This sensitive drum rotates in the direction of the arrow and in so doing successively arrives at the several treatment zones disposed about the periphery of the drum. The conductive base member 1 is grounded. First, the drum surface 3 receives either a positive or negative direct current corona discharge from a corona discharge apparatus having a discharge electrode 5 connected to a direct current source (a). Next, the drum surface is exposed to an image pattern by means of the exposing device 8 disposed next to the electrode 5 and at the same time receives a corona discharge current of asymmetrical wave form from a corona discharge apparatus 9 having a discharge electrode 10 connected to corona discharge current source of asymmetrical wave form. This is followed by an uniform illumination all over the surface area of the drum surface by means of a light source 11 to form on the drum surface latent electrostatic image of light and dark whose polarities differ from each other. This latent electrostatic image is developed by means of a magnetic brush 23 disposed inside of a developing device 22 with a toner 6 which has been charged with a charge opposite that of the latent electrostatic image whose development is desired. A transfer sheet 24 is fed to between a roll 25 and the sensitive drum and pressed against the drum surface by means of roll 25, and the transfer of the toner image take place at this point. The transfer sheet 24 to which has been transferred the toner image is conveyed to a fixing device 26 where the toner image is fixed. Thus, a copy of either a positive image or a reversed image can be obtained as desired with a sharp contrast and no such defects as fogging. Next, the photosensitive drum is removed of its charge by means of a corona discharge device having a discharge electrode 28 connected to an alternating current source C and cleaned at a cleaning apparatus 29 equipped with a toner removing brush 30, after which the reproduction operation is repeated.

The following example and controls are given for further illustration of the invention.

EXAMPLE 1

10 grams of an acrylic resin are added to 90 grams of copper-activated cadmium sulfide followed by the addition of a small quantity of a solvent and thorough commingling of the mixture to an extent such as not to crush the cadmium sulfide. The so obtained viscous substance is then applied to a paper which has been deposited with silver, the application being made to a thickness of 100 microns using a doctor knife, thereby forming a photoconductive coating on the paper. Next, a Lumilar (A polyethylene terephthalate film) film of about 12-micron thickness is superposed to the foregoing photoconductive coating surface with a binder to thus obtain a sensitive plate. The Lumilar surface of the

foregoing sensitive plate is then applied a corona discharge of +7KV to positively charge the Lumilar surface uniformly. Next, a 450-watt tungsten lamp is placed at a point one meter from the sensitive plate, and the surface of the plate is exposed through an optical system to an optical image for about one second. Simultaneously with the exposure to the optical image corona discharge current of asymmetrical wave form is applied to form a latent electrostatic image in the 10 Lumilar surface. The asymmetric corona discharge current of asymmetrical wave form is obtained in the case using a generating apparatus wired as shown in FIG. 7-1 and by applying the corona discharge electrode with an alternating current voltage of 8,000 volts and the open shield with 500 volts, while regulating the ratio of negative corona discharge to the positive corona discharge to a ratio of 3:1. After the formation of the latent electrostatic image, the plate is brought into an ambient light and developed with a positively charged toner, and as a result a good quality negative reproduction image without fogging and of small edge effect is obtained. Further, when a latent electrostatic image produced in similar manner is developed with a negatively charged toner, a good positive reproduction image is likewise obtained.

CONTROL I

A sensitive plate prepared by the procedure described in Example 1 is applied a +7,000V corona discharge, and its Lumilar surface is positively charged. Next, a 300-W tungsten lamp is placed at a point one meter from this sensitive plate, and the surface of the plate is exposed for about one second to an optical image through an optical system. Simultaneously with this exposure to the optical image a normal alternating current corona discharge is applied to the plate and a latent electrostatic image is formed in the Lumilar surface. The sensitive plate is then brought out to an ambient light and developed with a negatively charged toner, and as a result a positive reproduction image excessively fogged and of poor contrast is obtained. When the plate was developed with a positively charged toner, a negative reproduction image having an intense edge effect and of a poor quality usually characteristic of repulsion development is obtained.

CONTROL II

The sensitive plate of Example 1 is applied a +7,000V corona discharge, and the Lumilar surface is positively charged uniformly. Next, a 450-W tungsten lamp is placed at a point one meter from this sensitive plate, and the plate is exposed for about one second to an optical image through an optical system. Simultaneously with this exposure to the optical image a -7KV direct current corona discharge is applied and a latent electrostatic image is formed in the Lumilar surface. The plate is then brought out to an ambient light and developed with a negatively charged toner, and as a result a positive reproduction image having an intense edge effect and of a poor quality usually characteristic of repulsion development is obtained. On the other hand, when the plate is developed with a positively charged toner, a foggy negative reproduction image is obtained.

We claim:

1. An electrophotographic process which comprises the steps of

- a. applying a first charge by means of direct current corona discharge of a specific polarity to an overcoated photosensitive member selected from the group consisting of a three-layered overcoated sensitive member consisting of a conductive base, a photoconductive layer and a surface insulating layer, and a four-layered overcoated photosensitive member consisting of a conductive base, a photoconductive layer, a surface insulating layer and an intermediate insulating layer disposed either within the photoconductive layer or between the photoconductive layer and the conductive base;
- b. applying to the so charged sensitive member a second charge by means of a corona discharge current of asymmetrical wave form, said corona discharge being one in which the ratio of the discharge current of a polarity opposite that of the first charge (i_1) to the discharge current of the same polarity (i_2) ranges between 10:1 and 10:9 and simultaneously exposing said sensitive member through an original having an image pattern of light and shadow, the degree of asymmetry of said corona discharge current of asymmetrical wave form being of such sufficiency that the charged potentials of the light and dark areas of the photosensitive member are both transformed to opposite polarities and

- that a latent electrostatic image of the dark area of the same polarity as the first charge and a latent electrostatic image of the light area of an opposite polarity to that of the first charge are formed during the subsequent uniform illumination over the entire surface of the photosensitive member; and
- c. thereafter exposing said photosensitive member to a uniform illumination over the entire surface by means of an activating radiation to form a latent electrostatic image of the light area and a latent electrostatic image of the dark area, said latent electrostatic images being of opposite polarity to each other.

2. The process of claim 1 wherein the corona voltage of said corona discharge current of asymmetrical wave form is 5,000 - 10,000 volts.

3. The process of claim 1 wherein said ratio of $i_1:i_2$ ranges between 5:1 and 2:1.

4. The process of claim 1 wherein said overcoated photosensitive member comprises said three-layered overcoated photosensitive member.

5. The process of claim 1 wherein said overcoated photosensitive member comprises said four-layered overcoated photosensitive member.
